(57) **CLAIM**

The ornamental design for a toner cartridge, as shown and described.

DESCRIPTION

FIG. 1 is a top perspective view of a toner cartridge showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom perspective view thereof;

FIG. 9 is an enlarged top perspective view of the encircled portion of FIG. 1; and,

FIG. 10 is an enlarged top perspective view of the encircled portion of FIG. 8.

The dashed broken lines in the figures represent portions of the toner cartridge that form no part of the claimed design. The dot-dot-dash broken lines in the figures encircling portions of the claimed design that are illustrated in an enlarged view form no part of the claimed design.

1 Claim, 10 Drawing Sheets(56)
